Section 1, Public Law 690, August 8, 1946
Patent expires May 3, 1963

10 Claims. (Cl. 179—171)

1

The present invention relates to a superheterodyne receiver, and it particularly pertains to a sharp filter for selecting the carrier wave interposed in the intermediate-frequency amplifier of the receiver and comprising one or more resonant circuits the damping of which is controlled by an amplifier.

In this case the damping of the resonant circuits is reduced by means of feed-back coupling via one or more of the discharge systems belonging to the amplifier, or by a negative resistance appearing between two electrodes of one or more of these discharge systems. The term "selecting" is construed herein to include the accentuation of the carrier wave with respect to the side-band frequencies, as well as the separation or suppression of the carrier wave.

A receiver of this kind, for example, permits the elimination of the serious distortion which occurs when the carrier wave of the received signal is attenuated by selective fading more strongly than are the side-bands. This is ensured by utilizing a sharp filter in the receiving channel to accentuate the carrier wave with respect to the side-bands. Such accentuation is preferably accomplished by means of a filter comprising one or more resonant circuits the damping of which is reduced by an amplifier.

The invention more particularly relates to a form of construction of the above-described superheterodyne receiver wherein all the side-band frequencies are attenuated at least approximately in proportion to the attenuation of the carrier wave. According to the invention, to this end the received intermediate-frequency oscillations corresponding to the received carrier frequency and side-band frequency signals are transferred directly to the amplifier which reduces the damping of the resonant circuit or circuits of the sharp filter, and supplied indirectly to the filter via this amplifier, while the resulting intermediate-frequency oscillations to be supplied to the detector are composed of the initial intermediate frequency oscillations which, if desired, may be amplified by the amplifier and of the oscillations selected by the filter.

In a circuit arrangement according to the invention, the linear distortion which would occur if the intermediate-frequency oscillations to be supplied to the detector were solely derived from the sharp filter is almost completely eliminated. Another advantage consists in the suppression of the damping influence of the preceding intermediate-frequency circuit upon the filter, which influence would occur if the intermediate-fre-

quency oscillations were supplied directly to the filter.

Consequently, it is also desirable that the oscillations of intermediate-frequency corresponding to the carrier wave selected by the filter should be derived from the whole of the intermediate frequency oscillations via the amplifier, so that the damping of the following intermediate-frequency circuit does not affect the filter.

10 It is theoretically possible, it is true, to suppress the damping influence of the preceding and of the following frequency circuits by reducing the damping of the filter more strongly with the aid of the amplifier, but in practice the damping of the circuit would then have to be reduced to such extent that the stability is endangered, so that self-excitation could occur, for example with small variations of the circuit elements under consideration.

20 A particularly advantageous circuit arrangement is obtained if, in at least one stage of the amplifier, both the intermediate-frequency oscillations supplied directly to the amplifier and the oscillations selected by the filter are amplified.

25 The received intermediate-frequency oscillations are preferably transferred to an impedance included in the receiving channel in series with the output terminals of the filter, this series connection being coupled to the input electrodes of a discharge system with the aid of which the damping of the filter is reduced.

30 The intermediate-frequency oscillations may alternatively be transmitted to one of the control grids of a discharge system with the aid of which the damping of the filter is reduced while the output terminals of the filter are connected to another control grid and to the cathode of this discharge system respectively.

35 Since, as a rule, it is necessary for the damping of the filter to be strongly reduced, the damping-reducing amplifier is preferably provided with negative feed-back, and this in such manner that the damping of the filter is not reduced by the negative feed-back in itself. This step results in a considerable increase in stability of the circuit arrangement so that there is no danger of self-excitation in the case of strong reduction of damping of the filter.

40 If the received intermediate-frequency oscillations are transferred inductively to an impedance included in the receiving channel in series with the output terminals of the filter, it frequently occurs that the accentuation of the side-

bands is not wholly symmetric with respect to the carrier wave.

According to a recognition which also underlies the invention, this asymmetry is due to parasitic capacities which may exist between the preceding intermediate-frequency circuit and the said impedance, and between the said impedance and earth. According to the invention the disadvantageous consequences involved by the occurrence of these capacities are suppressed by connecting a condenser in parallel with the series-connection of the impedance and the output terminals of the filter and/or by the interposition of a condenser between the impedance and the preceding intermediate-frequency circuit, which condenser (condensers) is (are) so adjusted that the influence of the said parasitic capacities upon the resonance curve of the filter is neutralized.

The invention will be explained more fully by reference to the accompanying drawing showing, by way of example, one embodiment thereof.

The figure shows the intermediate-frequency portion of a receiver comprising a sharp filter for the selection of the carrier wave, a control voltage for the automatic frequency control being produced with the aid of a selective network which has two control rectifiers connected to it, and the intermediate-frequency carrier wave being maintained within the range of frequencies selected by the filter due to the tuning of the sharp filter being acted upon by the said control voltage. The filter also forms part of the above-mentioned selective network.

The intermediate-frequency portion of the receiver comprises an intermediate-frequency amplifying tube 1 which is coupled to the control grid circuit of a discharge tube 4 via a resonant circuit 2 tuned to the intermediate-frequency and an impedance comprising a coupling coil 3. The latter is in series with a filter which is constituted by a circuit the damping of which is reduced and which is constituted by a condenser 6 and two series-connected coils 7 and 8. Consequently, the received intermediate-frequency oscillations are transferred indirectly to the filter 5. The damping of circuit 5 is reduced by being connected in three-point arrangement to the discharge tube 4. This tube is also provided with negative feed-back by that the cathode lead includes a resistance 9 which is not bridged for intermediate-frequency current. The damping of filter 5 is, however, not reduced by the presence of this resistance. The anode circuit of the discharge tube 4 includes a resonant circuit 10 which is tuned to the intermediate-frequency and which is coupled by capacitive means to a diode-detector 11, the audio-frequency output voltage of which is supplied to an audio-frequency amplifier (not shown).

The circuit 2 has, in addition, coupled to it a circuit 12 which is also tuned to the intermediate-frequency and which has connected to it two pushpull connected control rectifiers (diodes) 13 and 14. The centre of circuit 12 is connected to the centre of the output resistance 15 of the two diodes 13 and 14 via a coupling coil 16 which is inductively coupled to the intermediate-frequency circuit 10. The circuit 5, 10 and 12 and the coupling coil 16, together with the rectifiers 13 and 14, jointly constitute a device for producing a control voltage for automatic frequency control, which control voltage is pro-

duced across the output resistance 15 previously mentioned.

The control voltage is supplied to the control grid of a discharge tube 17 which is shown as a triode and of which the anode current is led through a magnetising coil 18. The inductance coil 8 comprises a core of high-frequency iron which has the magnetising coil 18 arranged on it. By varying the direct current flowing through the said coil it is possible for the inductance of the coil 8 and hence for the tuning of the sharp filter circuit 5 to be varied within definite limits.

Due to the presence of the sharp filter circuit 5, the side-band frequencies of the intermediate-frequency signal are strongly attenuated with respect to the carrier wave, thus avoiding the danger that with selective fading an apparent overmodulation of the signal occurs which would involve a strong non-linear distortion of the low-frequency signal.

If, now, the intermediate-frequency signal to be supplied to the detector stage would be derived solely from the filter, a very serious linear distortion of this signal would result due to the side-band frequencies being unevenly attenuated by the filter. By the use of the invention, this linear distortion of the signal is avoided almost completely. It is true that in the circuit according to the invention the side-band frequencies are amplified to a considerably smaller extent than the carrier wave—this is the purpose of the sharp filter—but all these frequencies are attenuated at least approximately to the same extent with respect to the carrier wave. This may be readily appreciated when the filter is imagined as short-circuited; in this case the intermediate-frequency oscillations transferred to the impedance 3 are amplified in the normal manner. If, however, the filter is not short-circuited the oscillations selected by the filter must be added. In the resulting intermediate-frequency oscillations which are constituted by the sum of the selected oscillations and of the normally amplified oscillations the various side-band frequencies, apart from less important variations, are thus attenuated almost uniformly with respect to the carrier wave.

In one practical form of construction the carrier wave may thus, for example, be amplified 10 to 15 times with respect to the amplification of the side-band frequencies.

For the desired operation of the circuit arrangement it is necessary that the tuning frequency of the circuit 5 should always correspond within narrow limits to the intermediate-frequency carrier wave. This conformity is ensured by the automatic frequency control since when a deviation occurs between the said frequencies there is produced across the resistance 15 a control voltage of suitable polarity which changes the inductance of the coil 8 to such extent that the tuning frequency of the circuit 5 is approximately brought again in conformity with the carrier-wave frequency.

Due to the circuit 5 forming part of the network for the production of the control voltage, the control is highly sensitive to small variations in frequency.

The coupling coil 3 is coupled to the intermediate-frequency circuit 2 not only inductively but also by capacitive means via a variable condenser 19. In addition, a variable condenser 20 is connected in parallel with the series-connection of the coupling coil 3 and the circuit 5. The 75 parasitic capacities which exist between the in-

termediate frequency circuit 2 and the coil 3 and between the coupling coil 3 and earth respectively are connected in parallel with the condensers 19 and 20 respectively. When the condensers 19 and 20 were not present, these parasitic capacities could bring about asymmetry in the resonance curve of the filter so that the lateral bands would no longer be symmetrically attenuated with respect to the intermediate-frequency carrier wave.

According to the invention, this influence of the parasitic capacities on the resonance curve is neutralized by the arrangement of condensers 19 and 20. By means of a suitable adjustment of at least one of these condensers it is possible to obtain a filter exhibiting a symmetric resonance curve, due to which distortion of the signal is avoided.

What I claim is:

1. An amplifier circuit arrangement, particularly for use in a receiver for receiving signal voltages of carrier and sideband frequencies, comprising an amplifier having an input circuit and an output circuit, filter circuit elements sharply tuned to a frequency corresponding to said carrier frequency, means to apply a first signal voltage having frequency components corresponding to said carrier and said sideband frequencies to the input circuit of said amplifier, means to couple said filter circuit elements to said amplifier to derive a second signal voltage of frequency corresponding to said carrier frequency, means to apply said second signal voltage to the input circuit of said amplifier and to reduce the damping of said filter, and means coupled to the output circuit of said amplifier to derive an output voltage comprising said first signal voltage and said second signal voltage.

2. An amplifier circuit arrangement, particularly for use in a receiver for receiving signal voltages of carrier and sideband frequencies, comprising a resonant circuit for translating a first signal voltage having frequency components corresponding to said carrier and said sideband frequencies, an amplifier having an input circuit and an output circuit, filter circuit elements sharply tuned to a frequency corresponding to said carrier frequency, means to couple said resonant circuit to the input circuit of said amplifier to apply a signal voltage of frequency corresponding to said carrier and sideband frequencies to said amplifier, means to couple said filter circuit elements to said amplifier to derive a second signal voltage of frequency corresponding to said carrier frequency, means to apply said second signal voltage to the input circuit of said amplifier and to reduce the damping of said filter, and means coupled to the output circuit of said amplifier to derive an output voltage comprising said first signal voltage and said second signal voltage.

3. An amplifier circuit arrangement, particularly for use in a receiver for receiving signal voltages of carrier and sideband frequencies, comprising a resonant circuit for translating a first signal voltage having frequency components corresponding to said carrier and said sideband frequencies, an amplifier having an input circuit and an output circuit, a filter circuit sharply tuned to a frequency corresponding to said carrier frequency, means to couple said resonant circuit and said filter circuit in series to the input circuit of said amplifier to apply a signal voltage of frequency corresponding to said carrier and sideband frequencies to said amplifier, means to

couple said filter circuit to said amplifier to derive and apply to the input circuit of said amplifier a second signal voltage of frequency corresponding to said carrier frequency to reduce the damping of said filter, and means coupled to the output circuit of said amplifier to derive an output voltage comprising said first signal voltage and said second signal voltage and having carrier frequency components relative to sideband frequency components greater than the carrier frequency component of said first signal voltage.

4. An amplifier circuit arrangement, particularly for use in a receiver for receiving signal voltages of carrier and sideband frequencies, comprising a resonant circuit for translating a first signal voltage having frequency components corresponding to said carrier and said sideband frequencies, an electron discharge tube amplifier having a cathode, a first control grid, a second control grid and an anode, a filter circuit sharply tuned to a frequency corresponding to said carrier frequency, means to couple said resonant circuit to the first control grid of said amplifier tube to apply a signal voltage of frequency corresponding to said carrier and sideband frequencies to said amplifier, means to couple said filter to said amplifier tube to derive a second signal voltage of frequency corresponding to said carrier frequency, means to apply said derived signal voltage to the second control grid of said amplifier tube and to reduce the damping of said filter, and means coupled to the anode of said amplifier tube to derive an output voltage comprising said first signal voltage and said second signal voltage and having carrier frequency components greater than the carrier frequency component of said first signal voltage.

5. An amplifier circuit arrangement, particularly for use in a receiver for receiving signal voltages of carrier and sideband frequencies, comprising a resonant circuit for translating a first signal voltage having frequency components corresponding to said carrier and said sideband frequencies, an amplifier having an input circuit and an output circuit, a filter circuit sharply tuned to a frequency corresponding to said carrier frequency, means to couple said resonant circuit to the input circuit of said amplifier to apply a signal voltage of frequency corresponding to said carrier and sideband frequencies to said amplifier, means to couple said filter circuit to said amplifier to derive a second signal voltage of frequency corresponding to said carrier frequency, means to apply said second signal voltage to the input circuit of said amplifier and to reduce the damping of said filter, means to couple the output circuit of said amplifier to the input thereof to apply negative feedback thereto and to prevent said negative feedback from reducing the damping of said filter circuit, and means coupled to the output circuit of said amplifier to derive an output voltage comprising said first signal voltage and said second signal voltage and having carrier frequency components greater than the carrier frequency component of said first signal voltage.

6. An amplifier circuit arrangement, particularly for use in a receiver for receiving signal voltages of carrier and sideband frequencies, comprising a first amplifying stage, a resonant circuit for translating a first signal voltage having frequency components corresponding to said carrier and said sideband frequencies inductively

coupled to said first amplifying stage, a first capacitor coupling said resonant circuit and said first amplifier stage, an amplifier having an input circuit and an output circuit, a filter circuit sharply tuned to a frequency corresponding to said carrier frequency, means to couple said resonant circuit and said filter circuit in series to the input circuit of said amplifier to apply a signal voltage of frequency corresponding to said carrier and sideband frequencies to said amplifier, a second capacitor connected in parallel with said series connected resonant circuit and said filter circuit, means to couple said filter circuit to said amplifier to derive and apply to the input circuit of said amplifier a second signal voltage of frequency corresponding to said carrier frequency to reduce the damping of said filter, and means coupled to the output circuit of said amplifier to derive an output voltage comprising said first signal voltage and said second signal voltage and having carrier frequency components relative to sideband frequency components greater than the carrier frequency component of said first signal voltage, said first and said second capacitors having capacity values at which the influence of the parasitic capacities between said first amplifying stage and said resonant circuit and said filter circuit are neutralized.

7. An amplifier circuit arrangement, particularly for use in a receiver for receiving signal voltages of carrier and sideband frequencies, comprising a resonant circuit for translating a first signal voltage having frequency components corresponding to said carrier and said sideband frequencies, an amplifier having an input circuit and an output circuit, a filter circuit, means coupled to said resonant circuit and the output circuit of said amplifier automatically to tune said filter sharply to a frequency corresponding to said carrier frequency, means to couple said resonant circuit to the input circuit of said amplifier to apply a signal voltage of frequency corresponding to said carrier and sideband frequencies to said amplifier, means to couple said filter circuit elements to said amplifier to derive a second signal voltage of frequency corresponding to said carrier frequency, means to apply said second signal voltage to the input circuit of said amplifier and to reduce the damping of said filter, and means coupled to the output circuit of said amplifier to derive an output voltage comprising said first signal voltage and said second signal voltage.

8. An amplifier circuit arrangement, particularly for use in a receiver for receiving signal voltages of carrier and sideband frequencies, comprising a first amplifying stage, a resonant circuit for translating a first signal voltage having frequency components corresponding to said carrier and said sideband frequencies inductively coupled to said first amplifying stage, a first capacitor coupling said resonant circuit and said first amplifier stage, an amplifier having an input circuit and an output circuit, a filter circuit, means coupled to said resonant circuit and to the output circuit of said amplifier automatically to tune said filter circuit sharply to a frequency corresponding to said carrier frequency, means to couple said resonant circuit and said filter circuit in series to the input circuit of said amplifier to apply a signal voltage of frequency corresponding to said carrier and sideband frequencies to said amplifier, a second capacitor connected in parallel with said series connected resonant circuit and said filter circuit, means to couple said

filter circuit to said amplifier to derive and apply to the input circuit of said amplifier a second signal voltage of frequency corresponding to said carrier frequency to reduce the damping of said filter, and means coupled to the output circuit of said amplifier to derive an output voltage comprising said first signal voltage and said second signal voltage and having carrier frequency components relative to sideband frequency components greater than the carrier frequency component of said first signal voltage, said first and said second capacitors having capacity values at which the influence of the parasitic capacities between said first amplifying stage and said resonant circuit and said filter circuit are neutralized.

9. An intermediate frequency amplifier circuit arrangement, particularly for use in a superheterodyne receiver for receiving signal voltages of carrier and sideband frequencies, comprising a resonant circuit for translating a first intermediate frequency signal voltage having frequency components corresponding to said carrier and said sideband frequencies, an electron discharge amplifier tube having a cathode, a control grid and an anode, a filter circuit comprising a first capacitor connected in parallel with a first inductor and a second inductor connected in series, means to couple said resonant circuit and the first inductor of said filter circuit in series between the control grid and cathode of said amplifier tube to apply a signal voltage of frequency corresponding to said carrier and sideband frequencies to said amplifier, means to couple said filter circuit to the cathode of said amplifier tube to apply to the control grid of said amplifier tube a second intermediate frequency signal voltage of frequency corresponding to said carrier frequency to reduce the damping of said filter circuit, means coupled to the anode of said amplifier tube and to said resonant circuit to derive a frequency control voltage, a third inductor coupled to the second inductor of said filter circuit, means to apply said frequency control voltage to said third inductor to tune said filter sharply to an intermediate frequency corresponding to said carrier frequency, and means coupled to the anode of said amplifier tube to derive an output voltage comprising said first intermediate frequency signal voltage and said second intermediate frequency signal voltage and having carrier frequency components relative to sideband frequency components greater than the carrier frequency component of said first intermediate frequency signal voltage.

10. An intermediate frequency amplifier circuit arrangement, particularly for use in a superheterodyne receiver for receiving signal voltages of carrier and sideband frequencies, comprising a resonant circuit for translating a first intermediate frequency signal voltage having frequency components corresponding to said carrier and said sideband frequencies, a first electron discharge amplifier tube having a cathode, a control grid and an anode, a filter circuit comprising a first capacitor connected in parallel with a first inductor and a second inductor connected in series, means to couple said resonant circuit and the first inductor of said filter circuit in series between the control grid and cathode of said first amplifier tube to apply a signal voltage of frequency corresponding to said carrier and sideband frequencies to said amplifier, means to couple said filter circuit to the cathode of said amplifier tube to apply to the control grid of said first amplifier tube a second intermediate frequency signal volt-

age of frequency corresponding to said carrier frequency to reduce the damping of said filter circuit, a negative feedback resistor interposed between the first inductor of said filter circuit and the cathode of said first amplifier tube, a frequency responsive detector circuit coupled to the anode of said amplifier tube and to said resonant circuit to derive a frequency control voltage, a third inductor electromagnetically coupled to the second inductor of said filter circuit, a second electron discharge tube amplifier to apply said frequency control voltage to said third inductor automatically to tune said filter sharply to an intermediate frequency corresponding to said carrier frequency, and means coupled to the anode of said first amplifier tube to derive an output voltage comprising said first intermediate

frequency signal voltage and said second intermediate frequency signal voltage and having carrier frequency components relative to sideband frequency components greater than the carrier frequency component of said first intermediate frequency signal voltage.
